UNITED STATES PATENT OFFICE.

WILLIAM HALKYARD, OF PROVIDENCE, RHODE ISLAND.

BUTTON-FASTENER.

SPECIFICATION forming part of Letters Patent No. 364,013, dated May 31, 1887.

Application filed March 19, 1886. Serial No. 195,788. (No model.)

To all whom it may concern:

Be it known that I, WILLIAM HALKYARD, of the city and county of Providence, and State of Rhode Island, have invented certain 5 new and useful Improvements in Button-Fasteners, of which the following is a full, clear, and exact description, reference being had to the accompanying drawings, forming a part of this specification.

10 My invention relates to the devices known as "button-fasteners," which are designed to fasten and maintain the button securely in operative position.

15 The objects of my invention are to simplify and cheapen and to render more durable and efficient this class of devices.

20 To the above purposes my invention consists in the certain new and useful construction and arrangement of the several parts of the device, as hereinafter fully described and claimed.

25 The views are all enlarged in the accompanying drawings, in which Figure 1 represents a top view of a blank of my fastener as cut from sheet metal before being struck up. Fig. 2 represents a top view of my fastener, the securing-clips being struck up into operative positions. Fig. 3 represents a side view of Fig. 2 inverted. Fig. 4 represents a side perspective of my fastener, with a button (shown 30 in broken lines) fastened therein by means of the securing-clips engaging with the button-shank. Fig. 5 represents a modified form of my fastener in blank. Fig. 6 represents the 35 same as Fig. 5, but with the securing-clip struck up.

In the said drawings like numbers designate like parts throughout.

Referring to the drawings, 7 designates the 40 base-plate, which is a flat disk. Near the center of the base-plate 7 is punched or cut out the four-sided diamond-shaped frame 8, having the arms or clips 11, and which is integral with said base-plate at the point 9. 45 From the side of the frame 8, opposite the point 9, extends the flat tongue 10, which is integral with the frame. Both the frame and the tongue are cut out from the base-plate together when said plate is cut from the sheet

50 metal. The holding arms or clips 11 of the frame 8 are struck up into the securing-clips, which lie in planes oblique to the base-plate 7 and with their tips closely together, as shown in Fig. 2. The tongue 10 is left in normal position, and lies in the plane of the base-plate 55 flush with the surfaces of the same, and has a certain degree of resiliency given to it when displaced by virtue of the connected point 9.

The button 13, Fig. 4, has its shank placed in the securing-clips 11 by first raising the 60 outer free end of tongue 10 clear above the upper surface of base-plate 7 and threading the shank thereon, then sliding the button along the tongue and snapping it into the securing-clips 11, when the tongue 10 springs 65 back into its home or slot 12 and leaves the button confined in the securing-clips by its shank.

In Figs. 5 and 6 I show a modified form, wherein but one V-shaped securing-clip, 11, 70 is formed, together with its tongue 10, which here extends to the edge of the base-plate 7 and has the same spring action as in the primary form by virtue of the connected point 9.

In the modification the securing-clip or 75 holding-arm is struck up in an almost vertical position, Fig. 6, and a button may be secured to it by snapping it into the securing-clip 11, as above described in Fig. 4.

In using my fastener to mount a button on 80 fabrics, leather, or the like, in the usual manner, the shank of the button is forced through a perforation in the material and drawn to the opposite face, where the tongue of the fastener is passed through said shank, which 85 is snapped into the securing clip or clips, as before described. The material in this case lies between the button-head and the upper surface of the base-plate, which bears snugly against the under face of the material and 90 maintains the button securely in operative position.

Having thus described my invention, I claim as new and desire to secure by Letters Patent—

1. The combination, as hereinbefore set 95 forth, with a base-plate, of two substantially V-shaped securing clips or arms cut from reverse sides of the base-plate and bent up to-

ward each other and a tongue having a free end and integral with both of the said securing clips or arms, substantially as and for the purpose herein described.

5 2. The combination, with the base-plate 7, of the V-shaped securing-clip 11, integral at one end with said base-plate and provided at

the other end with the integral tongue 10, and the clip 11, bent up nearly at right angles to said plate and tongue, substantially as described.

WILLIAM HALKYARD.
